UNITED STATES PATENT OFFICE

2,499,164

BABY EDUCATOR

Clarence M. Richardson, Cleveland, Ohio

Application January 16, 1947, Serial No. 722,417

2 Claims. (Cl. 155—23)

1

This invention relates to devices for training and educating infants and more particularly to a device for supporting an infant while teaching it to walk.

Various wheeled devices and swings have been provided heretofore for the purpose of supporting an infant in such a position that his feet may touch the ground or floor so that the infant and the device may be propelled by the action of the child's feet, for teaching him to walk and supporting him until he has sufficient strength to support himself and has learned to walk. Children of the age at which they are about to learn to walk are very curious and expend a great amount of energy to satisfy their curiosity, and also in play with toys and other articles to which they may be attracted. To merely place a child in a device particularly built to teach him to walk is not always attractive to the child and he may not, and frequently will not, expend as much energy in trying to walk as he would in the pursuit of some attractive item. It is then an object of this invention to provide a carriage or support for an infant which is so connected to a table that the carriage may be revolved about the table by the efforts of the infant's legs as he moves about to reach and play with articles on the table.

Another object of this invention is to provide a device for teaching an infant to walk which comprises the combination of a table on which attractive articles may be secured and a swing rotatable about the table for supporting the infant in such a manner that his feet may touch the floor and he may move the swing or supporting device about the table by walking.

A still further object of this invention is to provide a device of this kind which is so constructed and arranged that the complete device is very stable so that it will not tilt or fall over or be otherwise displaced as a whole, irregardless of the movement of the child.

With the above and other objects in view, my invention consists in the arrangement, combination and details of construction disclosed in the drawings and specification, and then more particularly pointed out in the appended claims.

In the drawings,

Figure 1 is a side elevation of a baby educator or walking device constructed according to an embodiment of this invention,

Figure 2 is a top plan view,

Figure 3 is a vertical section taken on the line 3—3 of Figure 2,

Figure 4 is a fragmentary detailed section of the upper end of the pivot member.

5 Referring to the drawings, the numeral 10 designates generally a baby walker for supporting an infant while he is learning to walk, in a carriage rotatable about a table upon which various articles may be secured for attracting the infant's 10 attention. The baby walker or educator 10 is formed with an annular base 11, having a vertically extending pivot member or rod 12 fixed to the center of the base and extending upwardly therefrom. An annular table surface 14 is fixed to the pivot member 12 intermediate the length thereof and spaced upwardly from the base 11.

15 The table 14 is slidable vertically on the rod or pivot member 12 and may be secured in a selected vertical position by a set screw 15 which engages through a collar 16 fixed on the lower side of the table surface 14. The set screw 15 is adapted to bear against the outer edge of the pivot member 12 for locating the table surface in any 20 desired vertical position suitable to the size of the child. Hook eyes 17, or other suitable attaching devices are secured in the table surface 14 with the hook or eye on the upper surface thereof so that toys as 18 may be fixed to the top 25 of the table by a resilient fastening member or cord 19, to prevent the toys from falling off the table when they are handled by the infant.

20 The upper end of the pivot member 12 is reduced in diameter to provide a suitable bearing 30 for the infant supporting carriage and arm which are secured rotatably to the pivot member 12. A radially extending arm 20 is rotatably attached to the reduced portion 21 of the pivot member 12 and extends outwardly from the rod 12 in a plane substantially parallel to that of the table 14 and spaced upwardly from the table.

35 The inner end of the arm 20 is provided with a bearing 22 having a central bushing 24 which may be of bronze or other suitable wearing material and the bearing 22 is held against lateral or vertical displacement of the rod 12 by a washer 25 and nut 26 fixed on the uppermost end of the rod 12. An inverted U-shaped frame 27 is provided for supporting a swing or seat, or other suitable 40 device for supporting an infant outwardly from the table 14. The U-shaped frame 27 is formed with a rod or lug 28 fixed to the uppermost end of the bight thereof, which lug 28 is securely fastened to the outer end of the arm 20 by bolts 45 29 or other suitable fastening devices.

50 In a device as shown in the drawings, the arm 20 is tubular in construction, having the outermost end thereof bent at right angles downwardly so the lug 28 will slide within the tubular arm 55 20 and the bolts 29 pass through the center of the

arm 20 and lug 28. Wheels 30 are rotatably carried by the lower end of the frame 27 at the lowermost end of the side arms 31 of the frame 27 for supporting the frame for rotation about the table. The wheels 30 are journaled in U-shaped brackets 32 fixed to the lowermost end of the arms 31. The wheels 30 are disposed in such a manner that the plane of each wheel is perpendicular to a radius of the base 11 so that the frame may be rotated about the base 11 while the wheels and their supporting bracket 32 are held against rotation or castering.

A swing as 34 is resiliently supported in the frame 27 by a spring 35 fixed to the lower side of the center of the bight of the frame 27. The swing 34 is adapted to be supported at such a height that a child in the swing may touch the floor with his feet and by movement of his feet will move the frame 27 about the base 11 and the table 14. The base 11 is of sufficient diameter and the arm 20 of a suitable length that the weight of the child in the swing 34 will at no time have a tendency to tip the assembly over and the child is supported against falling from the walker 10.

I do not mean to confine myself to the exact details of construction herein disclosed but claim all variations falling within the purview of the appended claims.

What I claim is:

1. An infant walker of the kind described comprising a table and an infant supporting carriage rotatable about the periphery of said table by the infant, said table comprising a base, a table surface spaced upwardly from said base, said carriage comprising an inverted U-shaped frame, a seat

resiliently supported in said frame depending from the bight portion thereof and spaced from the side arms, and means connecting said frame and said table for movement of said carriage peripherally about said table by the infant.

2. An infant walker for teaching children to walk comprising a table, including a base and an annular table top spaced upwardly from said base, a carriage, said carriage comprising a vertical U-shaped frame, a seat depending from the bight portion of said frame, said seat being so located in said frame that the infant's feet may touch the floor, wheels on the lower end of the said arms of said frame, and means connecting said carriage to said table for peripheral movement thereabout by the infant.
